UNITED STATES PATENT OFFICE.

LE ROY E. JOLLS, OF DETROIT, MICHIGAN, ASSIGNEE, BY MESNE ASSIGNMENTS, TO
GLEASON WORKS, OF ROCHESTER, NEW YORK, A CORPORATION OF NEW YORK.

GEAR-GRINDING MEMBER.

Application filed August 2, 1923. Serial No. 655,246.

My invention relates to a grinding member made of abrasive material, and has to do more particularly with abrasive members such as are used for grinding gears.

5 In its specific aspect, the invention is concerned with a grinding member of annular face mill type for operating on gears having teeth curved lengthwise, or curved slots of other similar articles, and has for 10 its purpose to provide an abrasive member that will operate successfully under continuous working conditions, so that the grinding surface will not become glazed or clogged, and thereby rendered inefficient after operation for a time.

15 To these ends, the invention comprises the structure that will appear clearly from the following description, when read in conjunction with the accompanying drawings, the 20 novel features being pointed out in the claim following the description.

In the drawings:

Figure 1 is a sectional view of one type 25 of grinding member constructed in accordance with a preferred embodiment of the invention, and

Figure 2 is a bottom plan view of the same.

The invention may be successfully performed in different ways, and for purposes 30 of illustration, I have shown one form of grinding member incorporating the improvement, and intended for use in grinding curved tooth gears, although the application 35 of the invention is not confined to this particular structure, which is intended only by way of example.

In the structure disclosed, 1 designates a 40 grinding member or wheel attached by suitable instrumentalities to a head or support 2. The grinding member 1 is in one piece and formed of suitable abrasive material, as usual in this class of construction. It is of 45 annular face mill type such as employed for grinding the sides of lengthwise curved teeth on spiral or curved tooth gears and has a tapered cross-section to make it suitable for operation on generated involute gear teeth.

It has been found that where a continuous 50 unbroken grinding surface is employed in

work of this character, the grinding element loses its efficiency after being operated for a time, owing to a glaze or smooth surface forming thereon, as the result of continued action. This I overcome by providing the outer edge of the grinding member 1 with a series of notches or cut away portions 3, thus affording a series of spaced grinding members 4, and with such an arrangement, continued operation of the grinder does not 55 affect the grinding surface, other than to 60 wear it away.

The grinding member 1 is adapted to be rotated by suitable mechanism in a grinding machine, as usual in this type of apparatus, 65 and the principle of my improvement may be likewise applied to other types of rotary grinding members, such as circular disks in which the outer edge constitutes the grinding portion. Also, the result can be accomplished in other ways than cutting away or notching the grinding surface, so long as the effect is to produce alternately disposed 70 grinding portions and spaces, so that the grinding portions come into action successively upon the work being treated, instead of having a continuous and uninterrupted contact therewith.

While the invention has been described with reference to a particular embodiment, 75 this application is intended to cover any modifications or adaptations of my improvement coming within the underlying purpose of the invention or the scope of the following claim.

I claim:

A grinding member adapted for finishing the sides of teeth on curved tooth gears, consisting of an annular one-piece abrasive member having operative surfaces in converging relation to each other and engageable with adjacent groove bounding tooth faces, the outer edge of said abrasive member being provided with a series of recesses affording alternately arranged grinding 90 surfaces and spaces on both said converging operative surfaces.

In witness whereof, I have hereunto signed my name.

LE ROY E. JOLLS.
